SWINGABLY SUSPENDED ELECTRICALLY
DRIVEN CUTTER DEVICE

Ernest Paskell, Columbus, Ohio, assignor, by
mesne assignments, to Battelle Development
Corporation, Columbus, Ohio, a corporation of
Delaware

Application July 20, 1950, Serial No. 174,882

7 Claims. (Cl. 90—15)

1

This invention relates to electric motor suspension, and, more particularly, to a novel combination of an electric motor and means for its suspension.

There are occasions when it is desirable to be able to cause an electric motor and a tool driven thereby, such as a rotating cutting wheel, to approach a given object at a speed such that the cutting wheel upon contacting said object will not rebound therefrom. For example, when a grinding or cutting wheel contacts work that is being rotated, and it is desired to make an extremely light cut in that work, it is necessary that the cutting wheel contact the work very gently and continuously in order to achieve a uniform, continuous cut.

In the past this has been accomplished by various hand operated or machine operated, hand actuated devices which cause a cutting wheel, with or without a motor associated therewith, to contact the desired object. However, where an extremely shallow cut is to be made, for example as low as 1×10^{-3} cm. in depth, the devices of the prior art are unsatisfactory for such purposes. In fact, cuts of even much greater depth generally cannot be achieved by prior art devices.

Cylindrical film type resistors are frequently spiralled in order to increase their resistance. Quite often the film is extremely thin, as low as 1×10^{-7} cm. in thickness, and consequently the spiral cutting operation is an unusually difficult one. Devices of the prior art are unsatisfactory for such spiral cutting, due to the fact that uniformity of depth of cut, uniformity of spacing between cuts, and gentleness of contact of the cutting tool cannot be achieved.

It is, therefore, one object of this invention to provide a unique means for suspending an electric motor in combination with a cutting tool actuated by the motor whereby the cutting tool may be brought very gently into contact with the work, and maintained continuously in contact therewith.

It is another object of this invention to provide a support in combination with an electric motor and cutting wheel which will enable the cutting wheel to be readily withdrawn from contact with the work.

It is still another object of this invention to provide a device capable of making a very shallow cut.

It is a further object of this invention to provide a resistor spiralling device.

Various additional objects and advantages of this invention will become apparent from the following drawings, in which,

2

Fig. 1 is a side elevation view of this device, and Fig. 2 is a front elevation view of a modification of the device shown in Fig. 1.

Referring to the drawings and, more particularly, to Fig. 1, 10 is a rod-like support, or fulcrum, about which vertical supporting member 12 is free to rotate. Suspended from member 12 is electric motor 13 on the shaft 14 of which (see Fig. 2) is a cutting wheel 16. A stop 17 is provided at the upper end of rod 12 beyond the fulcrum 10.

Electric motor 18, which may be suspended or otherwise mounted so that it is free to move in an axial direction, rotates shaft 19 which is supported by and threadedly engages support 21 which is positioned on stand 22. Attached to shaft 19 is chuck 24 which is adapted to secure the work 26 therein. The work, as shown, is a cylindrical resistor which is to be spiralled. Electric motor 18 has a source of supply of electrical energy 27 associated therewith, while electric motor 13 has a source of supply of electrical energy 28 associated therewith.

In the embodiment of this invention shown in Fig. 1, a solenoid 29, provided with a source of electrical current 31, is positioned above fulcrum 10. This solenoid has an armature 32 which contacts rod 12 and holds rod 12 tightly against stop 17 when the solenoid is actuated as shown in dotted outline in Fig. 1.

In the embodiment shown in Fig. 2, instead of a solenoid arrangement, the fulcrum 10 is the shaft of an electric motor 34 having a source of electrical energy 35. In this embodiment shaft 10 and rod 12 are fixedly secured to prevent relative movement therebetween. Electric motor 34 is a type of electric motor commonly known as a damper motor which is not damaged when stalled and consequently when rotated in the proper direction functions in the same manner as does solenoid 29, namely, to keep rod 12 in contact with stop 17.

Fulcrum 10 is so located with respect to chuck 24 that cutting wheel 16 while rotating will be forced against the work 26 by the force of gravity. Such dynamic displacement from a freely hanging position will be determined by the desired depth of cut, the size of the particular work being cut, and the weight and size of the motor 13 and cutting wheel 16. For a small resistor, such as is shown in the drawings, this angular displacement is less than 1°.

Stop 17 is so positioned that when the solenoid 29 or electric motor 34 is actuated, the grinding wheel 16 will be out of contact with the work 26 and also out of the way so that the work may

be positioned in chuck 24 or removed therefrom.

While member 12 has been disclosed as a rigid member it is understood that coming within the purview of this invention would be a flexible member, and instead of a solenoid member 29 or a damper motor 34, an electromagnet (not shown) which would cooperate with electric motor 13, could be used to hold that motor out of contact with the work 26.

The operation of this device is as follows: When the grinding wheel 16 is at rest and not in contact with the work, it is held out of the immediate vicinity of the work, either by solenoid 29, or in the modification shown in Fig. 2, by motor 34. This position of motor 13 and grinding wheel 16 is shown in dotted outline in Fig. 1. To operate the device after work has been inserted in chuck 24 the current to the solenoid 29 or to motor 34 is turned off and simultaneously motor 13 is energized. Motor 13 is so positioned that the force exerted by its starting torque tends to move it in a right-hand direction, as shown in Fig. 1. Consequently, while the force of gravity would tend to make motor 13 move to the left, as shown in solid outline in Fig. 1, the starting torque of the motor will overcome the force of gravity and tend to move the motor in a right-hand direction. However, the motor and associated grinding wheel cannot move in a right-hand direction because stop 17 prevents this. Therefore, the motor and associated grinding wheel are held in equilibrium as the motor comes up to speed and until the starting torque decreases. As the starting torque force decreases it eventually decreases to a point where it is balanced by the force of gravity tending to move the grinding wheel and motor associated therewith in a left-hand direction. Since the starting torque decreases gradually in a high-speed electric motor, the grinding wheel and motor will very gently and very gradually tend to move in a left-hand direction as the force of gravity overcomes the force exerted by the starting torque. The net result is to bring the grinding wheel 16 into very gentle contact with the work 26 which is being revolved by motor 18.

The reason that stop 17 is employed is because the starting torque is so great that the motor and grinding wheel would be moved so far in a right-hand direction, as shown in Fig. 1, that when the starting torque is diminished the force of gravity would bring the grinding wheel into abrupt contact with the work 26. However, by using stop 17 and determining its position by the degree of force exerted by the starting torque of the particular motor employed, and the size of the work being spiralled, a very gentle initial contact will be realized and a very gentle cutting contact will be maintained. Such a motion is essential in spiralling resistors of extremely thin skin or film thickness.

When the desired cut has been made in the work, it is only necessary by a simple switching arrangement to cut off the source of electrical energy to the motor 13 and simultaneously to supply electrical energy to either motor 34 or solenoid 29 whereby the cutting wheel 16 will be instantly removed from the work, and the work may then be removed from chuck 24, and be replaced by new work. Electric motor 18 then has its direction reversed until the right-hand end of the work 26 is properly aligned with cutting wheel 14, and the cutting procedure is then repeated.

Of course, if a non-rigid rod 12 is used to

support the electric motor and grinding wheel associated therewith, and an electromagnet is used to hold the motor and cutting wheel out of contact with the work, such an electromagnet can also function as a stop to prevent excessive movement of the motor when starting. Moreover, while stop 17 has been shown positioned above the fulcrum it may be positioned below the fulcrum on the opposite side of rod 12.

It should be apparent from the above description that the utilization of this invention results in obtaining work having extremely fine cuts therein. When a resistor, such as a carbon film resistor, having an extremely thin film thereon is to be spiralled, this invention may be utilized in the spiralling thereof and will enable an extremely shallow cut to be made in the film of the resistor, and will prevent chipping of the resistive film at its initial contact with the rotating grinding wheel.

While this invention is particularly suited to the spiralling of resistors, it is to be understood that its functions are not limited thereto and that this particular unique suspension mechanism in combination with an electric motor and cutting wheel operated thereby is applicable to many other uses where a shallow controlled cut is to be made and it is desired that the cutting tool initially contact the work in a very gentle manner.

While this invention has been described in its preferred embodiment it is to be understood that the words used are words of description rather than of limitation and that changes within the purview of the appended claims may be made without departing from the true scope and spirit of the invention.

What is claimed is:

1. A cutting device, including a cutting means for making an extremely light cut, with a very gentle initial contact of the cutting means, on an article, and comprising rotative motor means and cutting means driven by said motor means, a fulcrum, said motor and cutting means being freely suspended from said fulcrum, means for selectively preventing said cutting means and said motor means from assuming a suspended position dependent solely on the force of gravity, and means for limiting the movement of said cutting means and said motor means to a suspended position other than that suspended position which is dependent solely on the force of gravity, said motor means being so positioned that upon starting, its starting torque will cause the motor means to move away from a suspended position which would be dependent solely on the force of gravity.

2. The structure set forth in claim 1, wherein said motor means comprises an electric motor, and wherein said cutting means is a rotative cutting means.

3. The structure set forth in claim 1, wherein in said motor means is an electric motor, and wherein said cutting means is a cutting wheel.

4. The structure set forth in claim 1, wherein in said motor means is an electric motor, said cutting means is a cutting wheel, and wherein rigid means is provided which is rotatably secured to and depends from said fulcrum, said motor and said cutting wheel being freely suspended from said fulcrum by said rigid means.

5. The structure set forth in claim 1, wherein in said motor means is an electric motor, and wherein said means for selectively preventing said cutting means and said electric motor from

assuming a suspended position dependent solely upon the force of gravity is a solenoid means.

6. The structure set forth in claim 1, wherein in said fulcrum comprises a shaft, and wherein means is provided for applying torque to said shaft, said motor means and cutting means being suspended from said shaft in substantially rigid relation thereto.

7. A spiralling device, including a cutting means, for making an extremely light cut, with a very gentle initial contact of the cutting means, on the surface of cylindrically shaped work, and comprising means for detachably holding said work, means for simultaneously rotating said work and effecting relative movement of said work and said cutting means parallel to the axis of said work, rotative motor means and cutting means driven by said motor means, a fulcrum, said motor and cutting means being freely suspended from said fulcrum, means for selectively preventing said cutting means and said motor means from assuming a suspended position dependent solely upon the force of gravity, and means for limiting the movement of said cutting means and said motor means to a suspended posi-

tion other than that suspended position which is dependent solely upon the force of gravity, said motor means being so positioned that upon starting, its starting torque will cause the motor means to move away from a suspended position which would be dependent solely upon the force of gravity.
